UNITED STATES PATENT OFFICE.

REGINALD M. ALLWORTH, OF HAMILTON, ONTARIO, CANADA, ASSIGNOR TO THE F. F. DALLEY CO., LIMITED, OF HAMILTON, ONTARIO, CANADA, A CORPORATION OF ONTARIO.

DEVICE FOR OPENING BOXES.

1,035,296.

Specification of Letters Patent.

Patented Aug. 13, 1912.

Application filed February 18, 1911. Serial No. 800,000.

To all whom it may concern:

Be it known that I, REGINALD M. ALLWORTH, a citizen of Canada, residing at Hamilton, in the Province of Ontario and Dominion of Canada, have invented new and useful Improvements in Devices for Opening Boxes, of which the following is a specification.

This invention relates to a device for opening boxes which are more particularly designed for packing shoe polishing paste or other material. In boxes of this character it is necessary to maintain a tight joint between the body and the cover so as to exclude air from the interior of the box and prevent the contents thereof from drying out or deteriorating when the same is stored for a considerable length of time.

It is the object of this invention to provide a cover lifter for boxes of this character which does not interfere with the tight joint between the body and cover, which permits of easily and conveniently lifting the cover from the body when it is desired to use the contents of the box, which can be produced at comparatively low cost and which permits of stacking the boxes in cases without requiring more room than that which is occupied by ordinary boxes.

In the accompanying drawings: Figure 1 is a front elevation of a box equipped with my improved cover lifter or opener in one of its forms and showing the cover in its closed position. Fig. 2 is a top plan view thereof. Fig. 3 is a vertical section in line 3—3, Fig. 1. Fig. 4 is a view similar to Fig. 1, but showing the cover lifter in a position in which it has raised the cover partly from the body. Fig. 5 is a fragmentary vertical section, on an enlarged scale, in line 5—5, Fig. 1. Fig. 6 is a front elevation of a box provided with a slightly modified form of my improved cover lifter. Fig. 7 is a fragmentary vertical section of a box showing another modification of my invention.

Similar letters of reference indicate corresponding parts throughout the several views.

The box in its general construction is similar to that now in common use and comprises a body of sheet metal or other material having a bottom or lower head 1 and an upwardly projecting annular flange 2 ar-

ranged at the edge of the bottom and provided near its upper edge with an outwardly bulging annular head 3, while the cover of sheet metal or other suitable material comprises a top or upper head 4 having a depending annular flange 5 at its edge, which normally fits around the flange of the body above said bead.

My improved cover lifter or opener which is applied to this box is constructed as follows: 6 is an upright lip which is preferably formed integrally with the flange of the cover at the lower edge thereof and bent upwardly along the outer side of said flange. 9 represents a lifting lever or key whereby the cover is raised from the body and which is pivotally mounted on the upper end of the lip so as to turn in a plane parallel with the side of the cover and body. The pivotal connection between the lifting lever and lip may be variously constructed, that shown in Figs. 1—5 being suitable and consisting of an eyelet hollow rivet punched outwardly on the upper part of the lip so as to form an opening 7 and a tubular rim, collar or neck 8. The lifting lever is provided centrally with an opening which receives the neck 8 on which the lever turns and is confined between the outer side of the lip and the laterally turned or upset outer end of the neck 8. In the construction shown in Figs. 1 to 5, the lip lies close against the flange of the cover and the pivot eyelet projects outwardly therefrom. At opposite ends or arms of the lifting lever the same is provided with two lifting lugs 10, see Figs. 2 and 3, which project inwardly toward the adjacent part of the flange of the cover and are arranged above the bead on the flange of the body. Upon turning this lever in one direction or the other, one of the lifting lugs is caused to bear upon the bead of the body and thereby partly lifting or prying apart the cover from the body, as shown in Fig. 4, after which the opening of the cover can be completed in the ordinary manner.

By providing the lifting lever with lugs on opposite sides of its pivot the opening of the cover can be effected by turning the lever in either direction. It is preferable to extend the lifting lugs inwardly far enough to cause them to bear against the flange of the cover, whereby the lifting lever is held

frictionally in place and enables the lever to be normally held in a horizontal position, as shown in Fig. 1, in which it presents a neat and attractive appearance when the 5 boxes are stacked for exhibition. Furthermore, by engaging the lifting lugs with the flange of the cover the same engage with the bead of the body over a large area, thereby insuring a firm grip of these lugs on the 10 bead and enabling the cover to be lifted effectively and also preventing the lugs from slipping off the edge of the bead. The turning of the lifting lever is preferably effected by means of a finger piece 11 project 15 ing outwardly or laterally from the upper edge of the lever, as shown in Figs. 1-5, but if desired this finger piece may be arranged at the lower edge of this lever, as shown in Fig. 6. The lever together with the lugs 20 and finger piece are preferably stamped from a single piece of sheet metal but if desired the same may be cast or otherwise constructed. If desired the lever may be arranged between the cover flange and a lip 13 25 and the lever may be pivoted on said lip by means of a pivot eyelet 12 formed on the lever and projecting outwardly into an opening in the lip 13, as shown in Fig. 7.

I claim as my invention:

30 1. A box comprising a body having a flange provided with an outwardly projecting annular bead, a cover having a flange fitting over the flange of the body and provided with an upwardly turned lip, and a 35 lever pivoted horizontally between its ends on said lip and provided at its opposite ends with lugs which project inwardly beyond the inner side of the lever and toward the flange of the cover and which are adapted 40 ed to engage with the upper side of the bead

on the flange of the body upon turning the lever.

2. A box comprising a body having a flange provided with an outwardly projecting annular bead, a cover having a flange 45 fitting over the flange of the body and provided with an upwardly turned lip, and a lever pivoted horizontally between its ends on said lip and provided at its opposite ends with lugs which project inwardly beyond 50 the inner side of the lever and toward the flange of the cover and which are adapted to engage with the upper side of the bead on the flange of the body upon turning the lever, said lever being also provided centrally 55 on its upper edge with an outwardly projecting fingerpiece.

3. A box comprising a body having a flange provided with an annular outwardly projecting bead, a cover having a flange 60 fitting around the flange of the body above the bead thereof and provided with a lip which is bent upwardly along the outer side of the cover flange and formed integrally therewith and which is provided with an 65 opening and a neck around the edge of said opening, and a lever which is provided with an opening and with a lug projecting inwardly beyond the inner side of the lever and toward the cover flange and which is 70 pivoted on the lip by inserting said neck into said opening of the lever and upsetting the free edge of the neck.

Witness my hand this 17th day of February, 1911.

REGINALD M. ALLWORTH.
